UNITED STATES PATENT OFFICE.

CHARLES A. SCHRANZ, OF PHILADELPHIA, PENNSYLVANIA, ASSIGNOR TO WALTER WOOD, TRADING AS R. D. WOOD AND COMPANY, OF PHILADELPHIA, PENNSYLVANIA.

GAS PRODUCER.

Application filed September 26, 1922. Serial No. 590,689.

To all whom it may concern:

Be it known that I, CHARLES A. SCHRANZ, a citizen of the United States, residing in Philadelphia, county of Philadelphia, 5 Pennsylvania, have invented certain Improvements in Gas Producers, of which the following is a specification.

My invention relates to certain improvements in gas producers of the type in which 10 a stirrer bar is rotated to agitate material in the upper portion of the fuel bed. The invention relates especially to a type of gas producer in which two stirrer bars are used, one moving in a circular path within the 15 path of the other.

The object of my invention is to construct the mechanism so that the fuel bed at and near its outer surface will be agitated in the same proportion as the center.

20 This object I attain in the following manner, reference being had to the accompanying drawings, in which:

Fig. 1 is a plan view of my improved gas producer;

25 Fig. 2 is a vertical sectional view on the line 2—2, Fig. 1;

Fig. 3 is a diagrammatic plan view showing the paths of the two stirrer bars in making one complete revolution of the gas 30 producer;

Fig. 4 is a diagrammatic plan view showing the paths of the stirrer bars in making three complete revolutions of the gas producer; and

35 Fig. 5 is a sectional plan view of a modification of the mechanism for carrying out my invention.

Referring to the drawings, 1 is the body of the gas producer, which has, at its upper 40 end, a ring 2 forming a water seal with a flange 3 of a top section 4 supported on beams 5 at one side of the producer. In the present instance, the top plate is stationary and the body portion is rotated by

45 any suitable mechanism. 6 is a feeder for fuel having a hopper 7. 8 is the gas outlet. 9 and 10 are two stirrer bars mounted, respectively, in bearings 11 and 12 of any suitable construction. These stirrer bars are 50 hollow and are curved at the lower end, as shown in Fig. 2. A water pipe 13 extends into each stirrer bar and water is circulated through the stirrer bars so that they are kept cool.

It will be noted that the stirrer bar 9 is nearer the center of the gas producer than the stirrer bar 10. On the stirrer bar 9 is a worm wheel 14, which meshes with a single screw worm 15 on a shaft 16 mounted in bearings 17 in the frame 18 located on the top section 4 of the gas producer. Secured to the stirrer bar 10 is a worm wheel 19, which meshes with a double screw worm 20, also secured to the shaft 16. The feeding mechanism is driven through bevel gearing 21 from the shaft 16, as clearly shown in Fig. 1. This feeding mechanism forms no part of the present invention.

The shaft 16, in the present instance, has a sprocket wheel 22 at one end, which is driven from any suitable power driven shaft so as to impart movement to the shaft 16. By making the worm 20 in the form of a double screw and twice the pitch of the worm 15, the stirrer bar 10 is rotated separately around its own axis at twice the speed of the stirrer bar 9.

Referring to Fig. 3, which illustrates the movement of the two stirrer bars in one revolution of the producer, it will be noted 80 that the stirrer bar 10 cuts the fuel bed in a path substantially similar to the path of the inner stirrer bar 9. It will also be noted that the mechanism is so timed that in making one revolution, the stirrer bars terminate 85 at a point some distance from the point at which the movement started. In the present instance, it is one-third the distance so that, when the producer shell makes three complete revolutions, the third convolution 90 terminates at the same point as the first convolution started, as shown in Fig. 4. This movement, as shown in Fig. 4, thoroughly agitates the fuel bed and the extent of the agitation is substantially the same at and 95 near the outer walls of the producer as at the center, owing to the fact that the stirrer bar 10 is driven at a greater speed than the stirrer bar 9.

While one method of increasing the speed 100 of rotation of the outer stirrer bar is illustrated, other means may be designed without departing from the essential features of the invention.

For instance, in Fig. 5, a construction is 105 illustrated in which the worm 20^a is the same pitch as the worm 15^a, but the diameter of the worm wheel 19^a is one-half the diameter

of the worm wheel 14^a, which causes the stirrer bar 10^a to be rotated at twice the speed of the stirrer bar 9^a.

It will be understood that, in some instances, the body portion of the producer may be stationary and the top section may be rotated, carrying with it the two stirrer bars. In this instance, as the top section rotates, the outer stirrer bar will be rotated at a greater speed than the inner stirrer bar, producing a diagram similar to that illustrated in Fig. 4.

While worm gearing is shown as the means for rotating the stirrer bars, it will be understood that other types of gearing may be used.

I claim:

1. The combination in a gas producer, of a body portion; a top section; two stirrer bars extending into the producer from the top section, one stirrer bar being located nearer the center of rotation than the other stirrer bar; and means for separately rotating the outer stirrer bar around its own axis at a greater speed than the inner stirrer bar.
2. The combination in a gas producer, of a body portion; a top section; means for rotating the body portion and the fuel bed within the body portion; two stirrer bars

extending through the top section and into the fuel bed, one stirrer bar being located nearer the center of rotation of the fuel bed than the other stirrer bar; and means for separately rotating the outer stirrer bar around its own axis at a greater speed than the inner stirrer bar.

3: The combination in a gas producer, of a body portion; means for rotating the body portion and the fuel bed therein; a top section; bearings on the top section, one bearing being located nearer the center of rotation than the other bearing; a stirrer bar mounted in each bearing and extending through the top section and into the interior of the body portion, said stirrer bars being curved at their lower ends; a worm wheel secured to each stirrer bar; a driven shaft mounted in bearings in the top section; and two worms on said shaft, one worm meshing with the worm wheel on the stirrer bar nearest to the center of rotation of the body portion, the other worm meshing with a worm wheel on the outer stirrer bar, the latter worm being double the pitch of the former worm so that the outer stirrer bar will be rotated at twice the speed of the inner stirrer bar.

CHARLES A. SCHRANZ.
